UNITED STATES PATENT OFFICE.

JULES H. VENON, OF NEW YORK, N. Y.

DESIGN FOR A CUP OR SIMILAR ARTICLE.

47,413.

Specification for Design.

Patented June 1, 1915.

Application filed November 18, 1913. Serial No. 801,749. Term of patent 7 years.

To all whom it may concern:

Be it known that I, JULES H. VENON, a citizen of the United States, and resident of the city, county, and State of New York, have invented a new, original, and ornamental Design for a Cup or Similar Article, of which the following is a specification, reference being had to the accompanying drawing, forming part thereof.

The figure is an elevation of a cup showing my new design therefor.

The design comprises a cup of peculiar outline, substantially as shown in the drawings.

I claim:—

The ornamental design for a cup or similar article, as shown.

JULES H. VENON.

Witnesses:

M. KASTOR,
A. LAVANOUR.
